United States Patent Office.

MICHAEL B. DYOTT, OF PHILADELPHIA, PENNSYLVANIA.

Design No. 2,805, dated October 22, 1867.

DESIGN FOR AN EMBLEM.

The Schedule referred to in these Letters Patent and making part of the same.

TO ALL WHOM IT MAY CONCERN:

Be it known that I, MICHAEL B. DYOTT, of the city of Philadelphia, in the State of Pennsylvania, have invented or produced a new and original Design for an Emblem to be worn by the members of a particular society; and I do hereby declare that the following is a full, clear, and exact description of the same, reference being had to the accompanying drawing, making a part of this specification, and to the letters of reference marked thereon.

Referring to the drawing, the emblem is shown consisting of a circular disk, A B, having on its face side, in bas-relief, a rising sun, c, illuminating the edges of clouds d below it, and surmounted by an arch, e, having upon its face the word "Progression," and three stars, f, at each end of the said word.

What I claim as my invention, and desire to secure by Letters Patent, is—
The design for an emblem herein set forth and shown.
